CLAIM

The ornamental design for a muscle apparatus, as shown and described.

DESCRIPTION

1. Muscle apparatus

1.1: Perspective

1.2: Front

1.3: Back

1.4: Left

1.5: Right

1.6: Top

1.7: Bottom

1.8: Perspective

1.9: Perspective

1.10: Perspective

1.11: Enlarged

Fitness equipment for shoulder opening and back correction and posture correction. The design can be shrunk, stretched, and folded for easy storage. The broken line circle with a curvy line and the number 11, shown in reproduction 1.1 indicates an enlarged portion of the design.
